227,266

COMBINED RECORDER AND PLAYBACK UNIT OR SIMILAR ARTICLE

Y. Alan Shimasaki, Tokyo, Japan, assignor to Lanier
Electronic Laboratory, Inc., Atlanta, Ga.

Filed Nov. 22, 1971, Ser. No. 201,268

Term of patent 14 years

Int. Cl. D14—01

U.S. Cl. D26—14 B

FIG. 1 is a perspective view of a combined recorder and playback unit;

FIG. 2 is a top plan view of the combined recorder and playback unit;

FIG. 3 is a front elevation view of the combined recorder and playback unit;

FIG. 4 is a right side elevation view of the combined recorder and playback unit;

FIG. 5 is a left side elevation view of the combined recorder and playback unit;

FIG. 6 is a rear elevation view of the combined recorder and playback unit;

FIG. 7 is a bottom plan view of the combined recorder and playback unit.

I claim:

The ornamental design for a combined recorder and playback unit or similar article, as shown.
